POLARIZED SWITCH

Application filed August 19, 1929, Serial No. 386,827, and in Germany August 20, 1929.

This invention relates to improvements in polarized switches or so-called oscillating relays, which are adapted to provide for the selective or reverse current protection of electrical apparatus.

Relays with permanent magnets have a very slight opening force and the permanent magnets lose their magnetism after a relatively short period of time. When the relays

10 are equipped with or constructed as electro-magnetically operated arrangements, an outside source of supply for the voltage coil must generally be provided, which auxiliary source it is often impracticable to arrange or even

15 impossible to obtain. The voltage coil of an electro-magnetically operated relay usually cannot be supplied from the system to be controlled because any break in the system will cause the relay to become immediately

20 inoperative.

It is, accordingly, among the objects of the present invention to provide a polarized switch or relay in which the voltage coil of the switch is supplied directly from the system to be controlled.

25 Another object of the present invention is to provide a voltage coil which is connected in parallel with an inductive resistance to the circuit to be controlled and which is directly supplied from such circuit.

Objects and advantages, other than those above set forth, will be apparent from the description and the drawing which shows a schematic embodiment of the present invention.

30 Referring to the drawing by characters of reference, reference numeral 1 indicates one portion of an electric circuit and 2 indicates another portion of the same electric circuit.

40 A rectangular magnetic core member 3 is arranged in suitable relation to line 1 and is formed with pairs of projections 4, 5 and 6, 7 extending inwardly from the sides of the core 3. Line 1 of the electric circuit is wound

45 about one leg of core 3 to form a current coil

8 which is connected with a fixed contact member 9. When current flows through line 1, a magnetic flux is set up through the leg of the core 3 on which the current coil 8 is wound in such manner that the flux flows across the space between the projections from 4 to 5. Projections 4 and 5 are accordingly polarized and form a north and a south pole respectively, as indicated.

50 Another portion of line 1 is connected with a movable contact member 10 which is mounted on a bell crank 11 supported in a suitable manner. The movable contact 10 is normally retained in contact with the fixed contact

55 member 9, by the action of a spring. A second current coil 12 is formed by winding the portion of line 1, leading from the movable contact 10 on bell crank 11, about the leg of core 3 on the opposite side to that portion

60 of the core 3 which carries coil 8. Coil 12 is wound in the opposite direction relative to coil 8 and accordingly produces a magnetic field in core 3 which polarizes the projections

65 6 and 7 in such manner as to form a north and a south pole therein respectively as indicated. The magnetic flux bridges the gap between projection 6 and 7 as is the case with respect

70 to projections 4, 5.

75 A voltage coil 13 is arranged between the pairs of projections or poles 4, 5 and 6, 7, and is connected across lines 1 and 2 in parallel with a resistance 14. The voltage coil creates a magnetic field in its immediate vicinity and the resistance in parallel therewith prevents immediate disappearance of such field

80 in case a short circuit or other failure occurs in the system. An armature 15 is pivotally arranged within the voltage coil 13 which magnetizes the armature to form a south pole

85 at the end of the armature adjacent projection 5 and a north pole at the end adjacent projection 6. A lever 16 is secured to armature 15 and is provided with a roller 17 which contacts with a portion of the bell

crank 11 upon which movable contact 10 is mounted.

When the current flows in the normal direction, core 3 is so magnetized by current coils 8 and 12 that the projections, 4, 5 and 6, 7 are polarized, as shown in the drawing.

The projections on the same side of the core are of the same polarity and the magnetic flux flows across the gaps between the poles in the same direction. The armature 15 is also polarized by the field of the voltage core 13 so that the south pole of the armature is formed adjacent to the south pole formed in projection 5 and the north pole of the armature is adjacent the north pole formed in projection 6. The two like poles tend to repel each other and therefore tend to rotate the armature 15 in a counter-clockwise direction in such manner that the lever 16 is moved out of contact with the bell crank 11. Such counter-clockwise movement is, however, limited by a stop 18 which is so positioned that armature 15 may move in a counter-clockwise direction for only a very limited distance. The armature is retained outside of the middle magnetic position, under normal conditions, by means of the stop 18 so that the device may be used as a maximum current relay which will operate upon occurrence of a forward short circuit after the voltage of coil 13 has reached zero.

When the direction of the current reverses, the polarity of projections 4, 5 and 6, 7, will also be reversed while the polarity of the armature 15 will remain unchanged. Under such circumstances, the poles of the armature 15 will be opposite in polarity to the polarity of the adjacent poles of the core and the unlike poles will be attracted in such manner as to move the armature 15 in a clockwise direction. Armature 15, in its movement in a clockwise direction, will accordingly cause roller 17 to press against bell crank 11 in such manner that movable contact 10 will be moved out of contacting relation with the fixed contact 9. It will be seen that reversal of the flow of current in an electric circuit having the present invention embodied therein, will act to open the circuit and that the present device will act to aid in retaining the circuit in its normally closed condition so long as the flow of current is not reversed.

Although only one embodiment of the invention has been illustrated and described, it will be understood that various other embodiments are possible, and that various changes may be made without departing from the spirit of the invention or the scope of the claims.

60 The invention claimed is:

1. In a switch of the class described, a core member comprising four legs interlinked in such manner as to form a closed magnetic circuit of parallelogrammatic contour, current windings arranged about two

oppositely disposed of said legs, a pair of projections extending into said member from each of the remaining of said legs, one pair of said projections constituting like magnetic poles of one polarity responsive to current in said windings, the other pair of said projections constituting like magnetic poles of polarity opposite to that of the first-mentioned polarity responsive also to current in said windings, a voltage coil arranged within said member between the said projections constituting the respective pairs of poles, an armature arranged within and polarized responsive to potential impressed upon said voltage coil, said armature being adapted for rotation responsive to polarization of said projections, and means associated with said armature adapted to interrupt the circuits for the flow of current in said windings and said coil responsive to rotation of said armature.

2. In a switch of the class described, a core member comprising four legs interlinked in such manner as to form a closed magnetic circuit of parallelogrammatic contour, current windings arranged about two oppositely disposed of said legs, a pair of projections extending into said member from each of the remaining of said legs, one pair of said projections constituting like magnetic poles of one polarity responsive to current in said windings, the other pair of said projections constituting like magnetic poles of polarity opposite to that of the first-mentioned polarity responsive also to current in said windings, a voltage coil arranged within said member between the said projections constituting the respective pairs of poles, an armature arranged within and polarized responsive to potential impressed upon said voltage coil, said armature being adapted for rotation responsive to polarization of said projections, and means associated with said armature adapted to interrupt the circuits for the flow of current in said windings and said coil responsive to rotation of said armature in one direction only.

3. In a switch of the class described, a core member comprising four legs interlinked in such manner as to form a closed magnetic circuit of hollow parallelogrammatic contour, current windings about each of two oppositely disposed of said legs, a pair of projections extending into said member from each of the two remaining of said legs, one pair of said projections constituting like magnetic poles of one or another polarity responsive to and in dependence on direction of current in said windings, the other pair of said projections constituting like magnetic poles of one or another polarity and opposite to that of the first mentioned polarity also responsive to and in dependence on the direction of current in said windings, a voltage coil arranged within said member

between the said projections constituting the
respective pairs of poles, an armature ar-
ranged within and polarized responsive to
potential impressed upon said coil, said ar-
mature being adapted for rotation in direc-
tion in dependence on direction of current
in said windings, and means associated with
said armature adapted to effect interruption
of the circuits for the flow of current in the
said windings and the said coil responsive
to rotation of said armature in one direction
only.
